UNITED STATES PATENT OFFICE.

PETER J. TRACY, OF HARTFORD, CONNECTICUT, ASSIGNOR TO THE OTAKA FABRIC COMPANY, OF HARTFORD, CONNECTICUT.

LIFTER DESIGN MACHINE.

Application filed May 7, 1926. Serial No. 107,515.

This invention relates to means for producing a design in a web of paper. This design may be produced by preferably wetting the paper and longitudinally corrugating it by means of a pair of annularly grooved rolls, one of which is lifted at intervals in order to produce a design in the paper web.

In the drawings Figure 1 represents a plan view and Fig. 2 a sectional view of the machine taken on the line 2-2 of Fig. 1.

10 and 11 show the frame of the machine, suitably tied by braces 12, 12. 13 shows the roll of paper, from which it passes over the 15 guide roll 14, and under rolls 15 and 16, and into the tank 17 where the paper is wetted. The wet web of paper 18 then passes upon the cylinder 19 which is annularly corrugated at 20. The paper then passes around 20 the corrugated cylinder 19 and under the small annularly corrugated roll 24. The cylinder 19 is mounted on a shaft 25, and is driven by gear 26, and operated by means of a pulley 27 or by any other suitable means 25. The small roll 24 is mounted upon the shaft 29 and is driven by gear 30 meshing into gear 26.

In order to produce the desired design which is shown in the web of paper at 32, 30 the roll 24 must be lifted away from cylinder 19 at intervals. This is accomplished by means of a cam 33, operating a lever 34 that may be provided with a roller engaging the cam 33. This lever 34 is pivoted at 35 and the other end of the lever supports the shaft 29, to which the small corrugated roll is connected. The lever 34 is supported in a bracket 36 which is fastened to frame of the

machine. This bracket 36 is provided with two upwardly extending parts 37, 38, in which the shaft 35 is pivoted. This bracket is also provided with a projecting portion 40 which supports the cam shaft 41. The cam shaft 41 is driven by means of a gear 42, which engages the cylinder gear 26. The near end 40 of the cam shaft is provided with a spline 43, and a nut 44. This nut may be unscrewed, in order that the cam 33 may be removed from the shaft, and another cam having different projections, may replace it. 45 This cam may be provided with as many projections as is desired for lifting the small corrugated roll at intervals desired, which may be regular or irregular. The lever 34 is pressed downwardly by means of a spring 45 50 55 55.

The corrugated roll 24 may be removed from lever 34 and from the arm 46, by removing caps 47 and a new roll may be substituted. The new roll may be provided with 60 cut away portions, if desired to produce modifications of the design.

Various modifications may be introduced in the construction of this machine without departing from the spirit of the invention. 65

I claim as my invention:

In a machine for producing designs in paper webs and in combination, a pair of annularly grooved rolls between which the paper web is passed whereby the web is longitudinally corrugated, a cam to separate the rolls at intervals to thereby provide alternate corrugated and plain portions in the web, and means to rotate the rolls and the cam. 70

PETER J. TRACY.
